The ornamental design for a golf tee support, as shown and described.

DESCRIPTION

FIG. 1 is a front view of a golf tee support showing my new design;

FIG. 2 is a rear view of the golf tee support;

FIG. 3 is a right side view of the golf tee support;

FIG. 4 is a left side view of the golf tee support;

FIG. 5 is a top view of the golf tee support;

FIG. 6 is a bottom view of the golf tee support;

FIG. 7 is a top front side perspective view of the golf tee support;

FIG. 8 is a bottom rear side perspective view of the golf tee support;

FIG. 9 is a cross-sectional view of the golf tee support taken along line 9-9 of FIG. 1; and,

FIG. 10 is a top front side perspective view of the golf tee support in use.

The broken lines in the drawings depict environmental structure and form no part of the claimed design.
